NECKTIE KNOT FORM

Felix Alva, New York, N. Y.

Application February 2, 1938, Serial No. 188,383

5 Claims. (Cl. 2—153)

This invention relates to a device adapted to be incorporated within a knot in a necktie and more especially to a device to give form and shape to a four-in-hand knot formed in a so-called string necktie.

It is among the objects of the present invention to provide a new and improved article of manufacture adapted to be removably inserted in a four-in-hand knot formed in a so-called string necktie whereby said knot presents a more pleasant and aesthetically satisfying appearance than would otherwise be the case.

Other objects, advantages and features of the device according to the present invention will be apparent to those skilled in the art during the course of the following description wherein a specific embodiment of the present invention, herein illustrated, will be described, it being clearly understood however that the illustrated preferred embodiment is given solely by way of example and is non-limitative.

In the drawing:

Fig. 1 is substantially a perspective view of a string tie tied in a four-in-hand knot, showing the device according to the present invention positioned as in use;

Fig. 2 is substantially a perspective view of a tie during the process of tying a four-in-hand knot therein, showing the article of manufacture according to the present invention in position for use;

Fig. 3 is a front elevational view of the now preferred embodiment of the present invention;

Fig. 4 is substantially a vertical sectional view of Fig. 3 taken along the line 4—4;

Fig. 5 is substantially a side elevational view of the structure illustrated in Fig. 3; and

Fig. 6 is substantially a top plan view of the now preferred embodiment of the present invention.

Regarded in certain of its broader aspects, the present invention comprises a block-like object essentially triangular in outline in vertical section and substantially rectangular in outline in horizontal section, having a vertically positioned slot formed therein extending through at least a major portion of said block, open at the sides thereof but not open at the top, whereby a pair of substantially parallel block-like members are provided, united together by a hemi-cylindrical cross member formed integral with said members and positioned with the curved portion of said hemi-cylindrical member pointing in a downward direction. A cutaway portion is provided upon one of said substantially parallel members extending from the lowermost portion thereof in a vertical direction to the top and passing over the upper part of said connecting cross member to terminate at the top portion of said other

block member positioned in substantial parallelism to said first mentioned block.

In order to facilitate a fuller and more complete understanding of the matter of the present invention the herein illustrated embodiment thereof will now be described. In this connection the article itself, best illustrated in Figs. 3, 4, 5 and 6, inclusive, will be first described and later the use of the article which is best illustrated in Figs. 1 and 2 of the accompanying drawing forming part of the disclosure.

Referring then to Figs. 3, 4, 5 and 6, it will be noted that the block generally designated at 10 is essentially triangular in vertical sectional view as shown in outline in Fig. 3, the corners 11, 12 and 13 being rounded substantially as shown. A slot 14 is formed in said block extending substantially throughout the length thereof, whereby a front portion 15 is held substantially parallel to the rear portion 16 by means including a hemi-cylindrical cross-piece 17 formed integral with said members 15 and 16. It is to be noted that the connecting member 17 is positioned with the curved part pointing downwardly, substantially as shown.

A channel-like cutaway portion 18 beginning near the bottom end of the block generally designated at 13 and vertically extending toward the top of said block, is formed in the front portion 15. It is to be particularly noted that the cutaway portion 18 increases in width and depth as the distance increases from the point of origin, namely, the bottom end 13 of the front portion 15 of said block. The channel-like cutaway portion is continued over the top of the structure comprising the members or elements 15, 17 and 16, it being observed that the channel 19 formed in the cross member 17 is relatively shallow as compared to the depth of the channel formed in the front portion 15 of the block. The channel 19 extends around to the rear face of the back portion 16, terminating in the upper portion thereof, substantially as shown in Figs. 4 and 6 and generally designated by the numeral 20.

Referring now to Figs. 1 and 2, it is to be noted that the slot 14 formed in the block generally designated at 10, is of width sufficient to readily accommodate superposed plies of a string tie whereby portions 21 and 22 of said tie can be crossed and positioned within said slot, substantially as shown in Fig. 2. It is to be understood, of course, that although the slot is made sufficiently wide to accommodate a double layer of string tie material as shown, the sides defining said slot are positioned sufficiently close to each other whereby the block generally designated at 10 can engage therewith and be frictionally held on said crossed portions of said tie. Having positioned the block on the crossed parts of the tie, as aforesaid, a four-in-hand knot is formed there-

in in substantially the usual manner by passing the end portion of the tie 23 around the other end portion 24, as generally designated at 25, then bringing the end 23 around the portion 26 5 of said tie, over the block 10 and through the loop formed in the portion 27 of said tie. As tension is placed on the end portion 23 the portions of the tie comprising the knot will be tightened and will assume the relationship illustrated 10 in Fig. 1, whereby it is to be observed that the front portion 23 of the tied tie will have a small depression 29 formed therein, substantially as shown, caused by the cutaway channel 18 formed in said block 10.

15 It will be noted that a tie tied in a four-in-hand knot with the article according to the present invention position in said knot is provided with a substantially firm support and form, tending to give it a pleasing appearance and 20 resisting changes in relative position of the portions of the tie comprising the knot during use. It is also to be observed that the small depression 29 formed in the front portion of the tie after 25 tying as above described, at least tends to impart an air of smartness to the tied tie which is difficult to obtain when no form is used.

It is to be understood that this improvement is capable of extended application and is not confined to the exact showing of the drawing 30 nor to the precise construction described and, therefore, such changes and modifications may be made therein as do not affect the spirit of the invention nor exceed the scope thereof as expressed in the appended claims.

35 What is claimed is:

1. An article of manufacture of the type described adapted to being incorporated in and lending shape to a four-in-hand knot formed in a string tie, comprising a block having outline 40 essentially triangular with rounded corners and apex pointing downwardly in vertical section, said block having a vertically positioned slot formed therein dividing said block into a front member and a rear member united by a cross 45 member formed integral with and positioned near the top of said front and said back members, the front face of said front member of said block having a groove formed therein extending vertically upward from the lower end 50 thereof, being continued across the top portion of said cross member and terminating on the back face of said back member near the top thereof.

2. An article of manufacture of the type described adapted to being incorporated in and lending shape to a four-in-hand knot formed in a string tie, comprising a block having outline 55 essentially triangular with rounded corners and apex pointing downwardly in vertical section, said block having a vertically positioned slot formed therein dividing said block into a front member and a rear member positioned in substantial parallelism with respect to each other 60 and united by a cross member formed integral with and positioned near the top of said front and said back members, the front face of said front member of said block having a groove formed therein extending vertically upward from 65 the lower end thereof, being continued across the top portion of said cross member and termini-

nating on the back face of said back member near the top thereof.

3. An article of manufacture of the type described adapted to being incorporated in and lending shape to a four-in-hand knot formed 5 in a string tie, comprising a block having outline essentially triangular with rounded corners and apex pointing downwardly in vertical section and essentially rectangular in horizontal section, said block having a vertically positioned slot formed therein dividing said block into a front member and a rear member positioned in substantial parallelism with respect to each other and united by a hemi-cylindrical cross member formed integral with and positioned near the top of said front and said back members, said hemi-cylindrical cross member being disposed with curved portion pointing downwardly, the front face of said front member of said block having a groove formed therein extending vertically upward from 20 the lower end thereof, being continued across the top portion of said cross member and terminating on the back face of said back member near the top thereof.

4. An article of manufacture of the type described adapted to being incorporated in and lending shape to a four-in-hand knot formed in a string tie, comprising a block having outline 25 essentially triangular with rounded corners and apex pointing downwardly in vertical section and essentially rectangular in horizontal section, said block having a vertically positioned slot formed therein dividing said block into a front member and a rear member positioned in substantial parallelism with respect to each other 30 and united by a hemi-cylindrical cross member formed integral with and positioned near the top of said front and said back members, said hemi-cylindrical cross member being disposed with curved portion pointing downwardly, the front face of said front member of said block having a groove formed therein extending vertically upward from the lower end thereof, being continued across the top portion of said cross member and terminating on the back face of said back member near the top thereof.

5. An article of manufacture of the type described adapted to being incorporated in and lending shape to a four-in-hand knot formed in a string tie, comprising a substantially hemi-cylindrical block positioned with curved portions pointing downwardly, downwardly dependent substantially parallel members formed integral 55 with and positioned on the front and rear ends of said hemi-cylindrical member, each of said downwardly dependent members being substantially triangular with rounded corners and apex pointing downwardly in vertical sectional outline and essentially rectangular in horizontal sectional outline, said front member having a groove formed therein originating at the lowermost point thereof extending vertically upwardly 60 across the top of said hemi-cylindrical member and terminating at the back face of the back dependent member near the top thereof, the depth and width of said groove in the front face of said member increasing as the distance from the point of origin increases.

FELIX ALVA.
